UNITED STATES PATENT OFFICE.

TRACY B. HATCH, OF MENOMONIE, WISCONSIN.

DESIGN FOR A STORAGE-BATTERY PLATE.

SPECIFICATION forming part of Design No. 35,072, dated September 10, 1901.

Application filed August 12, 1901. Serial No. 71,840. Term of patent 14 years.

To all whom it may concern:

Be it known that I, TRACY B. HATCH, a citizen of the United States, residing at Menomonie, in the county of Dunn and State of Wisconsin, have invented and produced a new and original Design for a Storage-Battery Plate, of which the following is a specification, reference being had to the accompanying drawings, forming a part hereof.

My design for a storage-battery plate is shown in the drawings by a perspective view in Figure 1, Fig. 2 being an enlarged section taken on line 2 in Fig. 1.

As shown in the drawings, the leading or material feature of my design consists in a rectangular grid A, formed with side bars a, end bars b, transverse bars or braces c, and inclined bars d, spaced apart and forming between them receptacles for the active material e.

Having described my invention, what I claim as new, and desire to secure by Letters Patent, is—

The design for a storage-battery plate, as herein shown and described.

In testimony whereof I have hereunto signed my name to this specification in the presence of two subscribing witnesses.

TRACY B. HATCH.
